OTHER PUBLICATIONSNS Breathe Clean Personal Smoke Filter [Jan. 11, 2022] found online [Jan. 11, 2022]—<https://newsuo.com/en/product/product-86-123.html>.*Primary Examiner — John A Voytek(57) **CLAIM**

The ornamental design for a personal air filter, as shown and described.

DESCRIPTION

FIG. 1 is a front elevational view of a personal air filter showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top perspective view thereof;

FIG. 8 is a bottom perspective view thereof;

FIG. 9 is a bottom perspective view showing the personal air filter in a disassembled state;

FIG. 10 is a top perspective view showing the personal air filter in a disassembled state; and,

FIG. 11 is an enlarged view of portion 11 in FIG. 9.

The broken lines in the drawings illustrate portions of the personal air filter which form no part of the claimed design.
